UNITED STATES PATENT OFFICE.

ARCHIE F. MANSFIELD, OF BRENTWOOD, CALIFORNIA.

ROAD MARKER.

Application filed March 20, 1923. Serial No. 626,408.

To all whom it may concern:

Be it known that I, ARCHIE F. MANSFIELD, a citizen of the United States, and resident of Brentwood, in the county of 5 Contra Costa and State of California, have invented certain new and useful Improvements in Road Markers, of which the following is a specification.

My invention relates to a machine for 10 applying a ribbon or strip of paint to a road surface whereby to indicate the portion of the road to be used by vehicles moving in either direction.

It is one object of my invention to provide a movable device designed to carry a 15 quantity of paint and equipped with suitable mechanism for applying the paint in the form of a bend upon the road surface over which it moves.

It is a further object of my invention to provide a vehicle of the character indicated 20 provided with a guage for positioning and guiding the paint applying mechanism.

It is a still further object of my invention 25 to provide suitable devices for feeding and applying the paint and steering the vehicle and to provide controlling devices therefor.

Finally, it is an object of my invention 30 to provide a device of the character indicated that will be simple in form, construction and operation, and highly efficient in its practical application.

In the drawing:

Figure 1 is a side elevation of the road 35 marker.

Figure 2 is a rear elevation of the same.

Figure 3 is an enlarged detail of the feed mechanism.

Figure 4 is an enlarged section on 4-4 of 40 Figure 1.

Referring more particularly to the drawing, 1 indicates a tank provided with a filling opening at 2 and a cap therefor at 3, a paint strainer being inserted in said opening at 5.

The tank 1 is mounted on a shaft 6 provided with steering knuckles at 7 and wheels 8. To knuckles 7 are attached rearwardly extending arms 9 which are joined 50 at their rear ends by a shaft 10 having a rack portion 11 in mesh with a pinion 12 which, in turn, is operated by a hand wheel 13 so that the revolution of wheel 13 in either direction will move the wheels 8 as 55 desired.

At 19 are bars mounted upon the sides of

tank 1 and extending rearwardly thereof, a shaft 15 being revolvably mounted therein and extending a distance both sides thereof as shown and carrying rear wheels 16-16. 60 Wheels 16 are adjustable longitudinally of shaft 15 by means of key 17 and set screws 18.

Bars 19 are extended and fitted with separable bearings 20 in which a shaft 21 revolves. On shaft 21 is fitted a sprocket 22 fitted with a chain 23 engaging a second sprocket 22^a on stub shaft 24 set in one bar 19, the sprocket 22^a carrying a gear 25 meshing with a gear 26 on shaft 15. By means 65 of this arrangement when the device moves forwardly the brush 26 mounted on the center of shaft 21 is revolved at the desired rate of speed in the direction indicated by the arrow. 70

In the bottom of the rear end of tank 1 is provided a discharge opening 27 regulated by a gate 28 operated by a screw 29. At 30 is a chute receiving paint from opening 27 and discharging at a point adjacent 80 to the road surface and close to the brush 26 as shown.

In the present case the tank 1 is fitted with a handle 31 and a drain valve at 32.

This device is particularly useful for 85 marking a center line on asphalt pavements of a given uniform width such as are commonly used in building western highways, whereby the width of pavement to be used by oppositely moving traffic is clearly designated. 90

Supposing the tank 1 is filled with paint, preferably white, the device is moved into position in the center of the pavement and wheels 16 are adjusted on shaft 15 so that 95 they run on either edge of the pavement. The gate 28 is now opened a distance to permit the paint to run down chute 30 to brush 26, and the vehicle is moved forward. The brush 26 now applies the paint to the 100 pavement in a band the width of which is determined by the width of the brush used. Since the brush rotates against the direction of movement of the vehicle no surplus paint is left on the pavement, the supply of 105 paint to chute 30 being just sufficient to keep the brush wet.

It is to be understood, of course, that while I have herein shown and described 110 one specific embodiment of my invention changes in form, construction and method of operation may be made within the scope

of the appended claims. Any suitable means of mounting and moving the tank 1 may be employed.

I claim:—

- 5 1. A marker comprising a wheeled tank, rearwardly extending bars secured to the opposite sides thereof, a shaft journaled in the bars and having its ends extending laterally beyond the tank, paint-applying means driven by the shaft, and gage wheels adjustably mounted on the shaft.
- 10 2. A marker comprising a wheeled tank, rearwardly extending bars secured to the opposite sides thereof, a shaft journaled in the bars and having its ends extending
- 15

laterally beyond the tank, gage wheels on the shaft, a second shaft journaled in the side bars, a brush on the second shaft, and means for driving the second shaft from the first shaft to rotate the brush against 20 the direction of travel.

3. A marker comprising a wheeled tank, rearwardly extending bars secured to the opposite sides thereof, a shaft journaled in the bars and having its ends extending 25 laterally beyond the tank, gage wheels on the shaft, and a brush journaled in the side bars and driven from the shaft, to apply the coating material from the tank.

ARCHIE F. MANSFIELD.
